UNITED STATES PATENT OFFICE.

ALPHONS J. WISSING, OF PEORIA, ILLINOIS, ASSIGNOR TO ILLINOIS BATTERY STEAMER CO., OF PEORIA, ILLINOIS, A CORPORATION OF ILLINOIS.

STEAMING DEVICE AND CONDENSER.

Application filed March 1, 1920. Serial No. 362,572.

To all whom it may concern:

Be it known that I, ALPHONS J. WISSING, a citizen of the United States, residing at Peoria, in the county of Peoria and State of Illinois, have invented certain new and useful Improvements in Steaming Devices and Condensers; and I do hereby declare that the following is a full, clear, and exact description of the invention, which will enable others skilled in the art to which it appertains to make and use the same.

This invention pertains to improvements in that class of devices known as battery steamers, also to a novel type of inlet for water for the same.

Battery steamers are of that type of steam producers from which steam is led into the jars of storage batteries for softening the composition of which their walls are made whereby the walls are caused to be made flexible or pliable by which the grids, which usually fit snugly, can be readily withdrawn and replaced. These steamers are usually so constructed that the working parts or joints of the float valve which provides for feed water and which joints lie within the vessel, and therefore quite hot, receive upon them the water as it enters, causing quick corrosion of such joints which ultimately prevents the valve from functioning properly.

It is usual to provide a condenser for the steamer by which distilled water may be produced for use in making the electrolyte for the battery, or for other purposes. The condenser, however, is usually a part separate from the steamer or still and connected with the same by a flexible tube or some form of piping, the steamer and condenser requiring separate water connections and by being thus constructed they are hardly in proper portable shape.

It is my purpose herein to combine a still and condenser as a unit readily transportable and readily boxed for shipment, ready to set up for operation, merely making a single water connection therewith, none of the parts being likely to be damaged because of the rigid relation of the same.

One of the objects of the invention is the provision of a valve of the float controlled type for feeding water to a vessel in which to create steam under more or less pressure, wherein the water is supplied as fast as required to maintain a given level.

Another of the objects is the provision of

a steam-creating vessel in which water is to be supplied as fast as used, a valve of the float operated type for supplying the water, the same being of such construction that the water will be introduced into the vessel without passing over any of the working parts of the valve to cause corrosion of those parts and eventually interference with free operation of the valve.

Another object is to provide a valve structure for a device of the kind described in which the float valve includes a duct for introducing water into the vessel from a position outside the latter whereby the water will not be brought into contact with any of the working parts.

Another object is that of mounting a portable condenser and steamer or still in rigid relation, the two having connection whereby steam produced in the latter will be condensed in the former through the use of a single water connection to both, the water flowing continuously through the condenser while being fed in a more or less intermittent manner automatically to the still through such single connection.

The appended drawing illustrates a preferred manner of constructing my combined still and a condenser and the valve used therewith, although changes may be made as may suggest themselves to the practical mind without sacrificing the spirit and intent of the invention.

Figure 1 is a vertical section of an apparatus involving my invention, and Fig. 2 is a longitudinal section of a valve shown in Fig. 1 very much enlarged.

The body of the steamer or still is represented by the numeral 1. It has a flange 2 at its upper edge upon which is secured in a steam-tight manner a plate 3. Mounted upon the still is a condenser body 4 closed at its bottom water-tight by a plate 5 secured to its flange 6, the still and condenser being spaced from one another substantially as shown, providing an insulating air space between them whereby heat will not be conducted to said condenser, 7 denoting a series of spacing bolts disposed around and extending through the flanges 2 and 6 for the purpose of such spacing. Within the condenser body is a worm 8, one end of which leads into the steam space of the still 1, its other end projected through the wall of said body for delivery of distilled water

from said worm, the body 4 being adapted to receive cooling water through a valved inlet pipe 9, the overflow of water being through an outlet 10.

5 In the wall of the still 1 is a cock 11, of which there may be several, each having a flexible tube 12 for conducting steam into the battery box or other place to receive steam.

10 13 denotes, as a whole, a valve secured to the side of the still above the water line. It comprises a threaded stem 14 having a flanged portion 14' adapted to be clamped upon the inner surface of the wall of said still, there being a gasket 15 interposed between it and said wall to make a tight joint. Depending from the flanged portion is an arm 16 to which is pivoted between its ends a rod 17 carrying at its long end 20 a float 18. The said stem 14 is provided with a bore 19 receiving a piston or plunger 20, having at one end outside the still a recess 21 for the reception of a valve-seat 22 of leather or other suitable material. The 25 opposite or inner end of the piston or plunger is slotted at 23, as is also the inner extremity of the stem 14 at 24 to receive the lever arm 25 pivoted at one end to the arm 26, for example, being part of the stem 30 structure. Between the other end of said lever arm 25 and the short end of the float carrying rod 17 is connected a link 27.

The stem 14 is securely held in place on the wall of the still by means of a lock-35 nut 28, the projecting portion receiving the main body 29 of the valve structure, held thereon through suitable fluid-tight connections not necessary to be described in detail. Said body 29 has a recess 30 therein in the 40 form of a bore into which the piston or plunger 20 extends, and within which it may move.

In one side of the body is a passage 31 connecting with the said recess or bore 30, 45 while a pipe 32 is connected with said passage 31 terminating within the still above the water line.

33 is a member having threaded engagement with the body 29 and having a longitudinal bore 33' extending therethrough, one end of said member extending into the recess or bore 30, its extremity therein adapted to receive upon it the seat 22 of the plunger 20. 34 is a locknut by means of 55 which, after adjustment, the member may be fixed in position.

35 is a passage or duct leading from the outer end of the body 29 to a recess 36 in the side of the latter into which is screwed 60 the pipe 9 mentioned earlier herein, and 37 is a feed pipe for water connected to the body 29 for introducing water into the bore 31' and the said passage 35.

The still is placed upon a suitable heater 65 and steam is conducted to the place for use

through the tube 12. In addition, the steam finds its way into the worm 8 where it is condensed due to the flow of cooling water entering the body 4 through the pipe 9. As the water in the still decreases in volume 70 the float 18 in descending with the lowering water level moves the lever arm 25 in a direction to remove the seat 22 from the member 33 to expose its bore 33'. The feed water under pressure in the said bore is thus 75 liberated into the bore 30, finding its way through the passage 31 and pipe 32 to the still until the water level is restored. The feed is necessarily slow from the fact that the conversion of the water into steam is 80 slow and in consequence the descent of the float is slow. The amount of water fed is not sufficient, therefore, at any time, to lower the water temperature in the steamer to a point where steaming will be greatly inter- 85 ferred with.

It has been customary to permit the flow of water past or along the plunger 20 entering the still through the bore of the stem 14, running down the lever arm 25. This 90 method has been found to be very undesirable, in fact detrimental, in that the cold water when flowing over the highly heated metal parts forms a deposit and corrodes the parts to such an extent that the joints 95 become stiffened and unyielding so that the float after a time ceases to properly respond to the gradual rise and fall of the water and because of this the water may drop to quite a low level before the float acts. That is 100 to say, the float having been left partially suspended will finally fall, perhaps when its weight overcomes the friction of the joints whereupon the water will rush in and attain too high a level before the float can 105 again respond. This is of course fatal to the desired steady steaming for battery use and desired rapid work.

In my form of apparatus the water is fed from a point in the valve body outside the 110 steamer or still, and since the bore 30, the passage 31, and the pipe 32 are quite large, they present a path of the least resistance and the flow of water will be through them, therefore, rather than between the walls of 115 the bore 19 and the plunger 20.

The adjustment of the member 33 serves to position the float 18 at any point desired at which the level is to be maintained. Obviously, the further in the member is turned 120 the lower the water level will be since the float will be pushed downward, while an opposite direction of adjustment of the member will have the reverse effect. The still or condenser, since fixed relatively to one another, can be connected by the single water feed arrangement and supplied from the single water connection. This is an important 125 advantage in a portable still and condenser and an outfit for the purposes set forth, since 130

the said outfit is a single unit ready for use at once by making the single connection for water thereto, and because of the rigid relation of the still and condenser the connection from one to the other cannot be broken or disarranged, causing leaks, as results when these parts are independent of one another.

Again, the water being practically undisturbed in the valve-body 29 which forms a "dead end" for the pipe 37, its temperature is maintained somewhat higher than the normal temperature in the mains from which it comes due to the conductivity of heat through the metal forming the wall of the still so that it will be in a more fit state to enter the latter without unduly affecting the steaming process. But at the same time the temperature will not be so high as to destroy its use for cooling the condensing worm 8. And although the cooling water for the condenser body is connected into the body 29 whereby it can be supplied from the pipe 37, a single connection, the steam cannot escape from the body 1 since the passages 30 and 31 are entirely separate therefrom.

I claim:

1. In combination, a still and a condenser-body, a valve-body connected with a source 30 of water supply separate from the still and condenser, a conduit connecting the valve-body with the still outside the latter, mechanism within the valve-body and a float within the still connected therewith for controlling the movement of the water through said conduit, a conduit connected at one end into the condenser body and at its other end connected with the source of water supply, and a valve in the last named conduit.
2. In a device of the nature described, in combination with a water supply pipe, a still and a condenser, a valve-body for attachment to said pipe, there being two 40 passages through said body separately connecting the pipe with the still and condenser, mechanism within said body for controlling the passage leading to the still, and a float in the still in control of said mechanism, the

other passage being in open connection with the pipe, and a valve in said passage that 50 leads to the condenser.

3. In combination, a still, and a condenser body including a condensing member connected with the interior of the still, a water supply pipe, a valve-body with which the 55 pipe is connected, a pipe connecting said valve-body with the still, a second pipe wholly separate from the last named pipe connecting the valve-body with the condenser body, and mechanism including a 60 float in the still for governing the flow of water through the said second pipe.

4. In combination, a still, and a condenser-body including therein a condensing member, a valve-body outside both the said still 65 and condenser-body including therein two separate and independent passages, a water-supply pipe connected with said valve-body for supplying water to both passages, a pipe 70 connecting one of the passages with the condenser-body, a pipe connecting the second passage with the still, a valve in said valve-body, and a float in the still for governing the flow of water through the second named passage by controlling said valve. 75

5. In combination, a still, and a condenser-body including therein a condensing member, a valve-body outside both the said still and condenser body including therein two 80 separate and independent passages, a water-supply pipe connected with said valve-body for supplying water to both passages, a pipe connecting one of the passages with the condenser-body, a valve in said pipe, a pipe connecting the second passage with the still, a 85 valve in said valve-body, and a float operatively connected therewith disposed within the still for governing the flow of water through the second named passage.

In testimony whereof I affix my signature 90 in presence of two witnesses.
